[57] CLAIM

The ornamental design for a front panel for a telephone control console, substantially as shown.

DESCRIPTION

FIG. 1 is a front perspective view of a front panel for a telephone control console;

FIG. 2 is a right side elevational view thereof;
FIG. 3 is a left side elevational view thereof; and
FIG. 4 is a top view thereof.

The broken lines shown in the drawings are for illustrative purposes only.
